**SYSTEM FOR COLLECTING AND DISPOSING OF
ORDINARY REFUSE BY CONVERTING IT INTO USEFUL
ENERGY, WITHOUT POLLUTION**

BACKGROUND OF THE INVENTION

1. Field of the Invention

This invention relates to the fields of refuse collection, disposal, energy generation, and pollution reduction, and in particular to a system accomplishing all four at the same time.

2. Description of the Prior Art

It has been estimated that the United States alone, presently generates one-half million tons of refuse per day. This "refuse explosion" comes at a time when increasing emphasis is placed upon reducing the pollution of our air, water and land. Prior art refuse disposal systems are not capable of disposing of refuse without generating pollution, and the prior art systems are becoming more expensive.

Prior art refuse disposal systems include (1) picking up the refuse, (2) transporting the refuse to a remote area, and (3) disposing of it. The prior art pickup requires an unusually large number of personnel (as measured by industry standards) and is thus unusually expensive for the amount of work accomplished. Trucks are used that are little, if any, advanced over wagons used thousands of years ago. The refuse must be hauled many miles to a remote area, because the manner in which the refuse is disposed of produces obnoxious odors and generally lowers property values in the area. As communities grow in size, the distance which the refuse must be hauled increases.

Prior art disposal is accomplished, for example, by incineration and landfill. Incineration produces great amounts of air pollution, leaves an unsightly "dump" area, and lowers surrounding property values. Landfill requires land to fill; as cities grow, additional land becomes more expensive, less available, and more distant from the point where the refuse is generated.

Regarding the energy-generating aspect of the present invention, it is estimated that the rate of increase of the need for useful energy in the world exceeds even the rate of increase of

SUMMARY OF THE PRESENT INVENTION

The present invention is a new method and apparatus (1) for collecting refuse, (2) for disposing of refuse, (3) for generating useful energy, (4) for reducing pollution, and (5) is also a new system combining various of the above listed (1-4) aspects of this invention.

In the preferred embodiment, the collecting is accomplished by means of grinder trucks for picking up and for 10 grinding up the refuse and by means of large tanker trucks for receiving the ground-up refuse from the grinder trucks and for transporting it to a large storage tank, conveniently located in the community.

In the preferred embodiment, the collected refuse is 15 disposed of and converted to useful energy; without pollution, by continuously feeding it into a liquid environmental combustion reactor, along with water and air. The temperature and pressure in the reactor are controlled such that the oxidizable matter in the refuse is oxidized generating heat, carbon dioxide, water, sulfur dioxide, nitrogen, and some light ash. The heat is used to generate both electricity and steam. For use in the present specification and claims, the term "refuse" is hereby defined to include waste, rubbish, trash, and debris and does not include sewage.

BRIEF DESCRIPTION OF THE DRAWINGS

The present invention will be more fully understood by reference to the following detailed description thereof, when 30 read in conjunction with the attached drawings, wherein like reference numerals refer to like elements and in which:

FIG. 1a and FIG. 1b show a schematic, flow diagram illustrating the various aspects of the present invention.

**DETAILED DESCRIPTION OF THE PREFERRED
EMBODIMENTS**

Before describing the method and apparatus of the present invention in detail, it is believed that reference to the following table, presenting a breakdown of the composition of 40 average municipal refuse, will aid the reader in understanding the present invention:

COMPOSITION AND ANALYSIS OF AN AVERAGE MUNICIPAL REFUSE

the population of the world. As conventional fuel sources become used up, more expensive fuels will be used. Further, electricity generating plants are usually located at large distances from population centers, while this is not necessary in the present invention. The present invention generates useful energy from refuse, which man has, from time immemorial, simply tried to get rid of, primarily by dumping it in someone else's back yard.

Referring now in detail to the preferred embodiments of the invention, the invention comprises picking up refuse from a home 2, where it is collected in garbage containers 4, by means of a grinder truck 6. The grinder truck 6 includes a grinder 8, a storage tank 9, and an inventory tank 10. A number of different grinders can be used, but the grinder 8 is preferably of the type which uses a steel bowl grinder tank on the bottom of which is a large rotating impeller disc with

pieces of tungsten carbide imbedded and welded therein, similar to that shown in U.S. Pat. No. 3,188,942. Grinding is accomplished by rapid rotation (for example, 600-1,800 r.p.m.) of the impeller disc. Clogging does not occur.

The ground-up refuse in storage tank 9 is periodically conveyed to a large tanker truck 12 having a storage tank 13, through a conduit 14, preferably connected to and unrolled from the tanker truck 12. The refuse can be forced through the conduit 14 by means of vacuum, a screw, a screw pump, etc., as will be understood by one skilled in the art. During the time that the refuse is being conveyed from the storage tank 9, to the tanker truck 12, the grinder 8 can continue to operate by switching the output from the grinder 8 to the inventory tank 10, through a conduit 11. After the storage tank 9 has been emptied, the conduit 11 is closed (by a valve not shown), the inventory tank 10 is emptied into the storage tank 9, and the conduit (not shown) from the grinder 8, to the tank 9 is opened. The volume of tank 13 of tanker truck 12 is much greater than the volume of tank 9 of truck 6, whereby many grinder trucks 6 can be serviced by a single tanker truck 12.

The tanker truck 12 transports its load, received from a large number of grinder trucks 6, to a large storage tank 16, by means of a feed conduit 18, preferably attached to the storage tank 9, for attachment to and removal from the tanker truck 12. The feeding through the conduit 18 can be accomplished by any of a screw, screw pump, vacuum, etc. The storage tank 16 can be so located that the truck 12 can drive on top of the tank 16 to use a gravity feed system. The volume of the stationary storage tank 9 is much greater than the volume of tank 13 of tanker truck 12. A plurality of storage tanks 16 can be used, depending upon the quantity of refuse being processed.

Another refuse pickup method can also be used, along with the method described above, as shown in the drawings. In this method, refuse from a source such as a house 20, collected in garbage containers 22, is picked up, by hand, for example, and deposited into a packet truck 24, of the type employing means for compacting the mass of refuse carried by it. The packer truck 24 unloads the compacted mass of refuse at a grinder building 26, having a conveyor 28 for feeding the compacted mass of refuse into a grinder 30. The ground-up refuse from grinder 30 is fed to storage tank 16 through feed line 32, by means for example, of a slurry pump 34, which includes a source of "dirty" water for mixing with the ground-up refuse to form a slurry. The term "dirty water" as will be understood by heat engineers, is to be distinguished from "water" meaning demineralized water. Alternatively, the refuse can be transferred from grinder 30 to tank 16 in solid form; it need not first be formed as a slurry.

The ground-up refuse in the storage tank 16 is fed continuously into a reactor 36, by means of, for example, a slurry pump 38, and a feed line 40. The ground-up refuse in the storage tank 16, is preferably formed as a slurry by introducing dirty water into the tank 16 from a source 41, through a pipe 43, for example. This is not necessary; the ground-up refuse can be fed into the reactor 36, as a solid. When the refuse is fed as a solid into the reactor 36, the water, or other liquid used, must be separately fed into the reactor 36. Air is also introduced into the reactor 36, preferably by means of a compressor 46 and air line 48.

In addition to using refuse as a fuel, it can be desirable at times to add other fuel values also into the reactor 36. This is accomplished by means of an alternative feeder 42 and feed line 44. The feeder 42 can include a grinder, for example, for grinding up trees, seaweed and any other oxidizable matter which may be available.

The oxidation process, and the start-up of the oxidation process, will be discussed after the following description of the remaining equipment used in the system.

An effluent conduit 50 carries the fluid effluent out of the reactor 36 from a point adjacent the top thereof, to a gas-liquid separator 54. Although the liquid component carries away some heat from the reactor 36, approximately 90 percent of the heat is contained in the hot gases.

The liquid component of the effluent, separated out by the separator 54, is fed through a conduit 56 containing a valve 52, to a settling tank 58. The valve 52 is preferably an automatic, pressure activated valve, set to open at a predetermined pressure. The valve 52 helps to maintain the desired pressure in the reactor 36. The material in the settling tank 58 can be periodically emptied through a discharge pipe 59. The component of the effluent includes sterile water and a light ash (the nonoxidizable matter in the refuse). The ash water can be discharged into a settling pond that empties through a sand filter into a nearby stream, leaving the light ash as a landfill residue.

The hot gaseous component of the effluent is fed through a conduit 60 to a steam generator 62, and then through a conduit 64, to a power recovery turbine 66. A combustion superheater 68 is maintained in the conduit 64 for heating the gases to raise their temperature. The turbine 66 drives both the compressor 46 to supply air to the reactor 36 and a generator 70, to generate electricity. The electricity is distributed via lines 72 to points of use, such as for example, building 74. The exhaust gases from the turbine 66 are fed through a conduit 76 to a cooling tower absorber 78 to prevent thermal pollution, and then to atmosphere.

Returning now to the steam generator 62, water (clean water) is fed into the steam generator 62, through a water inlet pipe 80, from, for example, a water source in a district heating system 82, diagrammatically illustrated in the drawings. The water is heated and converted to steam in the steam generator 62 by the heat contained in the gaseous effluent from the reactor 36. The generated steam is used, for example, for heating and cooling buildings in the community. The steam can be fed through a steam line 84, to an absorption heat exchanger refrigeration unit 86, connected to the building 74 by a conduit 87. The steam can also be fed directly to the building 74, through a steam line 88 and valve 89, for example, for heating purposes. It is noted that New York City, for example, has about 100 miles of steam lines, of the type illustrated in the drawing by reference number 84.

The above description is that of the system of the present invention during operation. In order to start up the process, the generator 70 is used as a motor to drive the air compressor 46 to feed air into the reactor 36. At the same time, steam is fed through a steam line 90, from an available source in the district heating system 82, to bring the reactor 36 up to starting temperature. After the oxidation process starts, it generates sufficient heat to maintain the oxidation, and a valve 92 in steam line 90 is closed.

Regarding the oxidation process carried out in the reactor 36, the liquid environmental combustion process of this invention operates on the principle that oxidizable matter can be oxidized, i.e. combined with oxygen, for combustion in hot, liquid surroundings as opposed to the usual hot air surroundings. The heat value that is available is released to the surrounding fluid, from the combination of carbon and oxygen, hydrogen and oxygen, and sulfur and oxygen, forming carbon dioxide, water and sulfur dioxide, respectively. This flameless burning is accomplished by introducing all of the collected and ground-up refuse into the reactor 36, along with the stoichiometric quantity of air, and along with sufficient liquid, such as water, to control the upper temperature limit of the material in the reactor 36. Other liquids than water that can be used include waste oil, for example. Further, oxygen can be fed into the reactor 36 rather than air.

In the preferred embodiment, using water and air, the pressure is maintained between about 600 and 4,500 p.s.i., the temperature is maintained between about 180° and 705° F., and the refuse is ground-up to a particle size of between about one-half and 1 inch diameter. Preferably, at least about 10 percent of the volume of the reactor 36 is in the solid state at any one time. The refuse and the air are introduced adjacent the bottom of the reactor 36 and the effluent is discharged adjacent the top of the reactor 36. The material in the reactor can be agitated, if desired, by ultrasonic agitation for example.

The generated steam can be used to generate electricity,

however steam requires more equipment and is more expensive for this purpose than are the exhaust gases in the conduit 64. Further, the use of the exhaust gases to generate electricity provides about 50 percent more thermal efficiency.

The invention has been described in detail with particular reference to preferred embodiments thereof, but it will be understood that variations and modifications can be effected within the spirit and scope of the invention as described hereinabove and as defined in the appended claims.

I claim:

1. A method for disposing of refuse comprising: collecting refuse, feeding the collected refuse to a liquid environmental combustion reactor, and oxidizing, in said reactor, all of the oxidizable matter in said refuse.
2. The method according to claim 1 including feeding the collected refuse to a grinder for grinding up the refuse, prior to feeding it to said reactor.
3. The method according to claim 2 in which said oxidizing step comprises: feeding a liquid into said reactor, feeding oxygen into said reactor, and maintaining the pressure and the temperature in said reactor within predetermined respective ranges.
4. The method according to claim 3 wherein said liquid feeding step comprises feeding dirty water into said reactor and wherein said oxygen feeding step comprises feeding compressed air into said reactor.
5. The method according to claim 3 including: discharging a hot fluid effluent from said reactor, and generating useful energy from the heat contained in said fluid effluent.
6. The method according to claim 5 wherein said generating step comprises feeding the gaseous component of said effluent to a steam generator for generating steam.
7. The method according to claim 2 in which said step of feeding the refuse to said reactor includes converting said ground-up refuse into a liquid slurry, and feeding said slurry to said reactor.
8. A method for disposing of refuse comprising: collecting refuse, said collecting step comprising: depositing the refuse to be collected in a grinder truck, grinding up the refuse in said grinder truck, storing the ground-up refuse in a storage tank on said grinder truck, feeding the collected refuse to a liquid environmental combustion reactor, and, oxidizing, in said reactor, all of the oxidizable matter in said refuse.
9. The method according to claim 8 including:

periodically conveying the ground-up refuse from said storage tank in said grinder truck to a larger storage tank in a tanker truck,

transporting the ground-up refuse in said tanker truck to a large stationary storage tank, and conveying the ground-up refuse from the large storage tank in said tanker truck to said stationary tank.

10. The method according to claim 9 including continuing to grind up refuse in said grinder truck while the storage tank in the grinder truck is being emptied and feeding the ground-up refuse, during said emptying, to a smaller inventory tank on said grinder truck.
11. A method comprising: feeding all of the municipal refuse to be disposed of in a given community to a liquid environmental combustion reactor, and oxidizing all of the oxidizable matter in said refuse, in said reactor, by the liquid environmental combustion thereof.
12. The method according to claim 11 including: grinding up, prior to said feeding step, all of said refuse to particles within a predetermined range of particle sizes.
13. The method according to claim 12 including generating useful energy from the excess heat resulting from said liquid environmental combustion.
14. Apparatus for disposing of refuse comprising: a plurality of grinder trucks, each of said grinder trucks having a refuse grinder mounted on the truck and a storage tank mounted on the truck and adapted to receive ground-up refuse from said grinder, a tanker truck having a storage tank having a volume substantially larger than that of the storage tank on said grinder truck, means for conveying ground-up refuse from a grinder truck storage tank to the tanker truck storage tank, a large stationary storage tank having a volume substantially larger than that of the tanker truck storage tank, means for conveying ground-up refuse from said tanker truck to said stationary storage tank, a liquid environmental combustion reactor, means for conveying ground-up refuse from said stationary storage tank to said reactor, means for feeding compressed air into said reactor, means for feeding dirty water into said reactor, and means for discharging a fluid effluent from said reactor.
15. The apparatus according to claim 14 including: means for separating the liquid from the gases in said effluent from said reactor, means for conveying the separated-out liquid component of the effluent to a settling tank, and means for generating useful energy from the separated-out gaseous component of the effluent.
